US00D919688S

(12) **United States Design Patent** (10) Patent No.: **US D919,688 S**
Takagi et al. (45) Date of Patent: **** May 18, 2021**

(54) **EAR OF ROBOT**

(71) Applicant: **SONY CORPORATION**, Tokyo (JP)

(72) Inventors: **Noriaki Takagi**, Kanagawa (JP);
Hiidenori Ishibashi, Tokyo (JP);
Goushi Koike, Tokyo (JP)

(73) Assignee: **SONY CORPORATION**, Tokyo (JP)

(**) Term: **15 Years**

(21) Appl. No.: **29/765,017**

(22) Filed: **Jan. 5, 2021**

Related U.S. Application Data

(63) Continuation of application No. 29/645,961, filed on Apr. 30, 2018, now Pat. No. Des. 916,160.

(57) **CLAIM**

The ornamental design for an ear of a robot, as shown.

DESCRIPTION

FIG. 1 is a front, top, right perspective view of an ear of a robot showing our new design;
FIG. 2 is a rear, bottom, right perspective view thereof;
FIG. 3 is a front elevational view thereof;
FIG. 4 is a rear elevational view thereof;
FIG. 5 is a right side elevational view thereof;
FIG. 6 is a left side elevational view thereof;
FIG. 7 is a top plan view thereof; and,
FIG. 8 is a bottom plan view thereof.
